DESIGN FOR AN ORNAMENT.

No. 38,807.

Specification for Design.

Patented Sept. 17, 1907.

Application filed August 10, 1907. Serial No. 388,065. Term of patent 14 years.

To all whom it may concern:

Be it known that I, JOHN W. TALBOT, a citizen of the United States, residing at South Bend, in the county of St. Joseph and State of Indiana, have invented a new, original, and ornamental Design for Ornaments, of which the following is a specification, reference being had to the accompanying drawing, forming part hereof.

The figure is a face view of the ornament representing my new design.

I claim:

The ornamental design for an ornament, as shown.

JOHN W. TALBOT.
